Wilmette, Ill.

Application April 10, 1950, Serial No. 154,984

14 Claims. (Cl. 34—82)

1

This invention relates to improvements in tumblers.

In the majority of the clothes tumblers in commercial use at the present time the drums thereof are supported on rollers which permit rotation of said drums on a horizontal axis. These rollers are positively driven and transmit rotational movement to the drum supported thereon. A supporting structure of this type is not entirely satisfactory for a number of reasons, among which are relatively rapid wear, a relatively large number of parts, and relatively high cost. This construction, however, is usually necessary in large machines.

In relatively small machines, the roller type of supporting structure can be avoided by connecting one end wall of the drum to one end of a coaxial shaft journalled in a bearing which supports both the shaft and the drum. This type of drum supporting structure is obviously more simple and more desirable than the roller type, but due to the cantilever type of support provided, the size and weight of the drum which can be supported thereby is limited to one which is relatively small.

Experience has shown that maximum drying efficiency is obtained when the warm drying air is introduced into the front of the rotating drum and caused to flow axially through said drum, being discharged at the rear. To date, however, no satisfactory tumbler structure has been developed in which the drum is carried by a coaxial rotating shaft, as described above, and in which the drying air flows through the drum from front to rear and out of a central rear discharge opening.

It is, therefore, a general object of the present invention to provide an improved tumbler wherein the drum is fixed on one end of a rotatable coaxial cantilever shaft which is mounted in a bearing, said tumbler being so constructed that drying air flows through the drum from front to rear and out of a central discharge opening.

A further object of the invention is to provide an improved tumbler having a rotatable drum wherein the drying air is caused to flow therethrough relatively close to the periphery rather than centrally.

A further object of the invention is to provide an improved tumbler of the class described wherein the drum is mounted in an enclosed casing, said casing being provided with a warm air inlet, and said drum being exposed exteriorly to the warm air, in addition to being constructed in a manner to provide for passage of said warm air therethrough.

5 A further object of the invention is to provide an improved tumbler of the class described having a drum formed with a rear end wall and wherein said wall has a central air outlet, said drum having a perforated auxiliary end wall spaced inwardly from said first-mentioned end wall to form an auxiliary end chamber therebetween, there being a shaft fixed to and projecting axially rearwardly from said auxiliary end wall through the central opening in said drum end wall, and there being a fixed housing having its interior in communication with said end wall central aperture and having an air outlet opening, said housing also carrying a bearing in which said shaft is rotatably journalled.

20 A further object of the invention is to provide an improved tumbler having a lint trap interposed between the drum and the exhaust blower, said lint trap being provided with a screen positioned so that the air being drawn from the drum by the fan must pass upwardly therethrough.

25 A further object of the invention is to provide an improved tumbler of the class described wherein the auxiliary end wall is provided with a central imperforate area of substantial size and with an annular perforated area surrounding said imperforate area to thereby cause the air flowing through the drum to flow adjacent the periphery of said drum and to thereby effect maximum drying efficiency.

30 A further object of the invention is to provide an improved tumbler of the class described which is relatively simple in construction, efficient in operation, and which is otherwise well adapted for the purposes described.

35 In the drawings accompanying and forming a part of this specification, wherein is shown one complete embodiment of the preferred form of the invention, and wherein like characters of reference indicate the same parts in all of the views:

40 Fig. 1 is a fragmentary vertical sectional view of the improved tumbler;

45 Fig. 2 is a fragmentary front elevational view of the improved tumbler with the door thereof removed and with parts being broken away for clarity; and

50 Fig. 3 is a fragmentary sectional plan view taken approximately along the line 3—3 of Fig. 2.

55 Referring to Figs. 1 and 2 of the drawing, the numeral 5 indicates a generally rectangular cabinet, preferably formed of sheet metal, having a top wall 6, side walls 7 and 8, and a front wall 9. The cabinet 5 is preferably open at the rear. A vertical wall or partition 10 extends trans-

versely of the cabinet in a position spaced from and parallel to the front wall 9. A horizontally extending shelf 11, of approximately the same size as the top wall 6, extends transversely of the cabinet 5 and is connected to the lower margin of the partition 10, as shown.

The front wall 9 is formed with a circular opening 16, the margins of which are defined by an inwardly projecting frusto-conical flange 12. A door 13 is suitably mounted for swinging movement on a vertical axis and is positioned to normally close the opening 16, as shown in Fig. 1. The shelf 11 is formed with an air inlet opening 14, and positioned below and in registration with the opening 14 is an air heating element 15 which may be of any suitable type.

The partition 10 is formed with a circular opening 17 which is coaxial with the opening 16 in the front wall 9; and mounted on the rear surface of the partition 10, in registration with the opening 17, is a housing 18. The housing 18 has an open forward end surrounding the aperture 17, and said housing also has an opening 19 in a side wall thereof adjacent the partition 10. In its rear end wall the housing 18 carries a bearing 20, as shown in Fig. 1. Rotatably journaled in the bearing 20 is a shaft 21 which has fixed to one end thereof, rearwardly of the bearing 20, a V-belt pulley 22. The shaft 21 projects forwardly of the bearing 20 and coaxially through the opening 17 in the partition 10.

Mounted on the shelf 11 below the housing 18 is an electric motor 23 which may have suitable reduction gearing incorporated therein, and which is provided with a driving V-belt pulley 24. An endless V-belt 25 drivingly connects the pulleys 24 and 22.

It is apparent that the front wall 9, partition 10, top wall 6 and shelf 11 form an enclosed fixed casing, having two openings therein other than the normally closed garment receiving opening 16, i. e., the air inlet opening 14 and the air discharge opening 17. Mounted within this enclosed casing for rotation coaxial with the shaft 21 is a cylindrical drum 26. The drum 26 preferably has an imperforate circular rear end wall 27, an imperforate circular front end wall 28, and an imperforate cylindrical side wall 29 connecting said front and rear end walls. The front end wall 28 is formed with a central garment receiving opening 30 through which the frusto-conical annular flange 12 of the cabinet front wall 9 coaxially extends. The diameter of the opening 30 is larger than the diameter of the opening 16, and therefore the flange 12 is spaced inwardly from the margins of the opening 30 to form an annular opening therebetween.

A circular auxiliary rear end wall 31 is fixedly mounted in the drum 26 spaced from and parallel with the rear end wall 27. The auxiliary end wall 31 is formed with an imperforate central area 32 of substantial size, and said wall is also formed with a perforated annular area radially outwardly from the area 32. The end wall 27 and the auxiliary end wall 31 define an auxiliary end space 34 therebetween. The rear end wall 27 is formed with a central tubular extension 35 which projects rearwardly therefrom coaxial with the shaft 21 and air discharge opening 17. The tubular extension terminates adjacent the partition 10, as at 36.

Fixed on the forward end portion of the shaft 21 is an elongated tapered hub 37 which is formed at its forward end with a circular plate or flange 38. The plate 38 is suitably fixed to the central

imperforate area 32 of the auxiliary rear end wall 31. The hub 37 extends through the tubular extension 35 and projects into the housing 18, said hub being of substantially smaller diameter than the tubular extension 35, as shown in Fig. 1 to provide an annular air passage through said extension around said hub.

An annular felt seal 39 is fixed to the forward surface of the partition 10 surrounding the opening 17 and in sealing contact with the periphery of the tubular extension 35 adjacent its rear end. The housing 18 is formed with an internal transverse partition 40 rearwardly of the opening 19 thereof, said partition having an aperture 41 coaxial with the shaft 21. Fixed to the partition 40 is a centrally apertured disc 42 through which the shaft 21 projects. The disc 42 carries an annular felt seal 43 which sealingly engages the periphery of shaft 21.

As is clearly shown in Fig. 1, the front wall 9, top wall 6, partition 10, and side walls 7 and 8 are lined with suitable, preferably fireproof heat insulating material. The door 13 is also lined with the same type of heat insulating material. The layer of insulation 44 lining the vertical partition 10 is formed with an aperture 45 coaxial with the shaft 21, which aperture is of substantially larger diameter than the felt seal 39.

Mounted on the rear surface of the vertical partition 10 within the cabinet 5 is a rectangular lint trap 46. The lint trap 46 is provided with side walls 47 and 48, front and rear walls 49 and 50 respectively, and top and bottom walls 51 and 52 respectively. The side wall 48 is fixed to the housing 18 and is formed with an aperture 53 of substantially the same size as and in registration with the side opening 19 of the housing 18. The side wall 48 is formed with a second opening 54 adjacent the upper end thereof, and mounted on the outer surface of the wall 48, with its inlet opening in communication with the aperture 54, is an exhaust blower 55 which blower may be driven by an electric motor 56. The exhaust blower 55 has a discharge connection 57 projecting through the top wall 6 of the cabinet 5 adjacent the rear edge thereof. Mounted on suitable supporting brackets 58 on the inner surfaces of the side walls of the lint trap 46 is an angularly disposed screen 59, which screen is positioned substantially midway of the height of the lint trap 46 and between the apertures 53 and 54, as clearly shown in Fig. 2.

Operation

In operation, garments to be dried are introduced into the drum 26 through the garment receiving openings 16 and 30 in the wall 9 and in the drum 26, respectively. The motor 23, through the pulleys 22 and 24 and belt 25, rotates the shaft 21 and drum 26 at a predetermined speed, thereby causing tumbling of the garments within the drum. The exhaust blower 55 creates a suction at the aperture 54 of the lint trap 46 and causes air to flow through the improved tumbler in a manner to be now described.

The air which is drawn through the improved tumbler enters the open rear of the cabinet 5 below the partition 11 thereof. It is drawn into the opening 14 in the shelf 11, and as it is drawn through the opening 14, it is heated by the heating element 15. The exterior of the rotating drum 26 is exposed to the incoming heated air, and said air flows toward the front of the cabinet 5 where it then flows radially toward the annular opening between the flange 12 and the

aperture 30 of the drum front end wall 28. As shown by the arrows in Fig. 1, the heated air enters the drum 26 through the annular space just referred to and flows toward the rear of the drum.

Since the tubular extension 35 forms the only outlet from the drum 26, the air must pass through the perforated area 33 of the auxiliary end wall 31 and radially inwardly within the auxiliary end space in order to reach the tubular extension 35. By having the auxiliary end wall 31 formed with a central imperforate area of substantial size and with an annular perforated area outwardly thereof and adjacent the periphery, the air flowing through the drum is made to flow adjacent the periphery thereof, as indicated by the arrows. This provides a drying action of maximum efficiency since the maximum amount of contact of the drying air with the garments in the drum is provided, and a flow of air axially through the center of the drum is thereby avoided.

The air flows from the tubular extension 35 into the housing 18, out of the side wall opening 19 of said housing through the aperture 53, and into the lint trap 48. As indicated by the arrows in Fig. 2, the air then flows upwardly through the screen 59, out of the aperture 54 and into the blower 55, from which it is discharged through the connection 57. As the air passes through the tubular connection 35 and housing 18, the felt seals 39 and 43 prevent leakage which would reduce the efficiency of the machine and cause short circuiting or bi-passing of the air travel. Any heavy lint that is carried by the air into the lint trap 46 drops to the bottom of the lint trap 46 (from which it may be periodically removed), and the lighter lint is collected on the underside of the screen 59.

It is apparent that the improved tumbler construction provides efficient operation, not only due to the fact that the heated air is caused to flow in a manner to utilize the maximum amount of heat content therein, but also the air is caused to flow through the drum 26 in a manner to dry the garments in the tumbler with maximum speed. In addition, the improved tumbler combines these advantageous features in a construction wherein the drum is supported at the end of a single rotating shaft.

Various changes and modifications may be made without departing from the spirit of the invention, and all of such changes are contemplated, as may come within the scope of the claims.

We claim:

1. In a tumbler: a rotatable drum having an air inlet opening and having an end wall formed with a central opening; an auxiliary end wall in said drum spaced inwardly of said first-mentioned end wall and forming an auxiliary end chamber therebetween, said auxiliary end wall being formed with an air passage therethrough; a drum supporting shaft fixed to said auxiliary end wall and projecting axially outwardly through the central opening of said first-mentioned end wall; a fixed housing surrounding a projecting portion of said drum supporting shaft and having an air inlet opening in registration with the central opening of said first-mentioned end wall, said housing also having an air discharge opening; and a bearing carried by said housing in which said drum supporting shaft is journaled for rotation.

2. In a tumbler: a rotatable drum having a

front end wall formed with an air inlet opening and having a rear end wall formed with a central opening; an auxiliary end wall in said drum spaced inwardly of said rear end wall and forming an auxiliary rear end chamber therebetween, said auxiliary end wall being formed with an imperforate central area of substantial size and with a plurality of air passages therethrough positioned radially outwardly of said imperforate area; a drum supporting shaft fixed to said auxiliary end wall and projecting axially rearwardly through the central opening of said rear end wall; a fixed housing surrounding the projecting portion of said drum supporting shaft and having an air inlet opening in communication with the central opening of said rear end wall, said housing also having an air discharge opening; a bearing carried by said housing in which said drum supporting shaft is journaled for rotation; and means for rotating said drum supporting shaft to cause rotation of said drum.

3. In a tumbler: a rotatable drum having an air inlet opening and having an end wall formed with a central opening; an auxiliary end wall in said drum spaced inwardly of said first-mentioned end wall and forming an auxiliary end chamber therebetween, an axially bored elongated hub formed at one end with an enlarged portion fixed to said auxiliary end wall, said end wall being formed with perforations outwardly of said hub portion and said hub projecting axially outwardly through the central opening of said first-mentioned end wall; a drum supporting shaft fixed in the bore of said hub and projecting axially outwardly therefrom; a fixed housing surrounding said drum supporting shaft and having an air inlet opening in registration with the central opening of said first-mentioned end wall, said housing also having an air discharge opening; a bearing carried by said housing in which said drum supporting shaft is journaled for rotation; and means for rotating said drum supporting shaft to cause rotation of said drum.

4. In a tumbler: a rotatable drum having an air inlet opening at one end and having an end wall formed with a coaxial tubular extension; an auxiliary end wall in said drum spaced inwardly of said first-mentioned end wall and forming an auxiliary end chamber therebetween, an axially bored elongated hub formed at one end with a coaxial circular portion fixed to said auxiliary end wall, said end wall being formed with perforations outwardly of said hub portion and said hub projecting axially outwardly through the tubular extension of said first-mentioned end wall; a drum supporting shaft fixed in the bore of said hub and projecting axially outwardly therefrom; a fixed housing surrounding a projecting portion of said drum supporting shaft and having an air inlet opening in registration with the tubular extension of said first-mentioned end wall, said housing also having an air discharge opening; a bearing carried by said housing in which said drum supporting shaft is journaled for rotation; and means for rotating said drum supporting shaft to cause rotation of said drum.

5. In a tumbler: a fixed enclosed casing having an air inlet opening and having a rear wall formed with an aperture therein; a rotatable drum in said casing having an imperforate side wall and having an imperforate rear end wall formed with a coaxial rearwardly directed tubular extension in registration with said casing rear wall aperture, said drum also having a front end wall formed with an air inlet; an auxiliary end

wall in said drum spaced inwardly from the rear end wall thereof and forming an auxiliary rear end chamber therebetween; said auxiliary end wall being formed with an imperforate central area of substantial size and with a perforated area radially outwardly of said imperforate area; a drum supporting shaft fixed at one end to said auxiliary end wall and projecting axially rearwardly through the tubular extensions of said drum rear end wall and through the aperture in the casing rear wall; a fixed housing mounted on the outer surface of said casing rear wall and having an air inlet opening in registration with the aperture in the casing rear wall; said housing surrounding a projecting portion of the drum supporting shaft and having an air outlet opening; and a bearing carried by said housing and in which said drum supporting shaft is journaled for rotation.

6. In a tumbler: a fixed enclosed casing having an air inlet opening and having a rear wall formed with an aperture therein; a rotatable drum in said casing having an imperforate side wall and having an imperforate rear end wall formed with a coaxial rearwardly directed tubular extension in registration with said casing rear wall aperture, said drum also having a front end wall formed with an air inlet; an annular sealing ring carried by said casing rear wall and surrounding said tubular extension, said ring forming a seal between said casing wall and said tubular extension; an auxiliary end wall in said drum spaced inwardly from the rear end wall thereof and forming an auxiliary rear end chamber therebetween; said auxiliary end wall being formed with an imperforate central area of substantial size and with a perforated area radially outwardly of said imperforate area; a drum supporting shaft fixed at one end to said auxiliary end wall and projecting axially rearwardly through the tubular extension of said drum rear end wall and through the aperture in the casing rear wall; a fixed housing mounted on the outer surface of said casing rear wall and having an air inlet opening in registration with the aperture in the casing rear wall, said housing surrounding a projecting portion of the drum supporting shaft and having an air outlet opening; and a bearing carried by said housing and in which said drum supporting shaft is journaled for rotation.

7. In a tumbler: a fixed enclosed casing having an air inlet opening and having a rear wall formed with an aperture therein; heating means positioned to heat air entering said casing; a rotatable drum in said casing having an imperforate side wall and having an imperforate rear end wall formed with a coaxial rearwardly directed tubular extension in registration with said casing rear wall aperture, said drum also having a front end wall formed with an air inlet; an auxiliary end wall in said drum spaced inwardly from the rear end wall thereof and forming an auxiliary rear end chamber therebetween; said auxiliary end wall being formed with an imperforate central area of substantial size and with a perforated area radially outwardly of said imperforate area; a drum supporting shaft fixed at one end to said auxiliary end wall and projecting axially rearwardly through the tubular extension of said drum rear end wall and through the aperture in the casing rear wall; a fixed housing mounted on the outer surface of said casing rear wall and having an air inlet opening in registration with the aperture in the casing

rear wall, said housing surrounding a projecting portion of the drum supporting shaft and having an air outlet opening; and a bearing carried by said housing and in which said drum supporting shaft is journaled for rotation.

8. In a tumbler: a fixed enclosed casing having an air inlet opening and having a rear wall formed with an aperture therein; heating means adjacent said casing air inlet opening for heating the air entering said casing; a rotatable drum in said casing having an imperforate side wall and having an imperforate rear end wall formed with a coaxial rearwardly directed tubular extension communicating with said casing rear wall aperture, said drum also having a front end wall formed with an air inlet; an auxiliary end wall in said drum spaced inwardly from the rear end wall thereof and forming an auxiliary rear end wall chamber therebetween; said auxiliary end wall being formed with an imperforate central area of substantial size and with a perforated area radially outwardly of said imperforate area; an axially bored elongated hub formed at one end with an enlarged portion fixed to the imperforate area of said auxiliary end wall, said hub projecting axially rearwardly through the tubular extension of said rear end wall and through the aperture in the casing rear wall; a drum supporting shaft fixed in the bore of said hub and projecting axially rearwardly therefrom; a fixed housing mounted on the other surface of said casing rear wall and having an air inlet opening in registration with the aperture in the casing rear wall; said housing surrounding the drum supporting shaft and having an air outlet opening; and a bearing carried by said housing and in which said drum supporting shaft is journaled for rotation.

9. In a tumbler: a rotatable drum having a supporting shaft projecting axially from one of its ends and having an air outlet opening adjacent said supporting shaft; a fixed housing surrounding a portion of said shaft and having an end air inlet opening in registration with the outlet opening of said drum; a bearing for said drum supporting shaft carried by said housing at the end thereof which is opposite to said air inlet opening, said housing also being formed with a side air discharge opening intermediate said air inlet and bearing; a partition in said housing intermediate said discharge opening and bearing, said partition being formed with an aperture through which said shaft projects; and a shaft seal carried by said partition and surrounding said shaft.

10. In a tumbler: a rotatable drum having a supporting shaft projecting axially from one of its ends and having an air outlet opening adjacent said supporting shaft; a fixed housing surrounding a portion of said shaft and having an end air inlet opening in registration with the outlet opening of said drum; a bearing for said drum supporting shaft carried by said housing at the end thereof which is opposite to said air inlet opening, said housing also being formed with a side air discharge opening intermediate said air inlet and bearing; a box-shaped lint trap having a side wall opening in registration with the side air discharge opening of said housing, said lint trap having a discharge opening above its side wall opening; and an exhaust blower having an inlet connection communicating with the discharge opening of said lint trap.

11. In a tumbler: a rotatable drum having a supporting shaft projecting axially from one of

its ends and having an air outlet opening adjacent said supporting shaft; a fixed housing surrounding a portion of said shaft and having an end air inlet opening in registration with the outlet opening of said drum; a bearing for said drum supporting shaft carried by said housing at the end thereof which is opposite to said air inlet opening, said housing also being formed with a side air discharge opening intermediate said air inlet and bearing; a box-shaped lint trap having a side wall opening in registration with the side air discharge opening of said housing, said lint trap having a discharge opening above its side wall opening; a screen extending across the interior of said lint trap intermediate said lint trap openings; and an exhaust blower having an inlet connection communicating with the discharge opening of said lint trap.

12. In a tumbler: a rotatable drum having an air inlet opening in an end wall and having a second end wall formed with a central opening; an auxiliary end wall in said drum spaced inwardly of said second-mentioned end wall and forming an auxiliary end chamber therebetween, said auxiliary end wall being formed with an air passage therethrough; a drum supporting shaft fixed to said auxiliary end wall and projecting axially outwardly through the central opening of said second-mentioned end wall; a housing surrounding a projecting portion of said drum supporting shaft and having an air inlet opening in registration with the central opening of said second-mentioned end wall, said housing also having an air discharge opening.

13. In a tumbler: a rotatable drum having a front end wall formed with a ring-shaped air inlet opening between the center of the drum and the periphery and having a rear end wall formed with a central opening; an auxiliary end wall in said drum spaced inwardly of said rear end wall and forming an auxiliary rear end chamber therebetween, said auxiliary end wall being formed with an imperforate central area of a size

substantially greater than the central opening and with a plurality of air passages therethrough positioned radially outwardly of said imperforate area; a drum supporting shaft fixed to said auxiliary end wall and projecting axially rearwardly through the central opening of said rear end wall; a bearing in which said drum supporting shaft is journaled for rotation; and means for rotating said drum supporting shaft to cause rotation of said drum.

14. In a tumbler: a rotatable drum having a supporting shaft projecting axially from one of its ends and having an air outlet opening adjacent said supporting shaft; a fixed housing surrounding a portion of said shaft and having an end air inlet opening in registration with the outlet opening of said drum; a bearing for said drum supporting shaft at the end of said housing which is opposite said air inlet opening, said housing also having an air discharge opening located intermediate said air inlet and bearing; a partition in said housing intermediate in said discharge opening and bearing, said partition having an aperture through which said shaft projects, and a shaft seal between the shaft and opening in the partition.
